COMBUSTION DEVICE FOR DOING AWAY WITH EXHAUST-GASES IN COMBUSTION-ENGINES.

939,844.

Specification of Letters Patent.

Patented Nov. 9, 1909.

Application filed August 20, 1909. Serial No. 513,734.

To all whom it may concern:

Be it known that we, KARL LEHMANN and ERNST LEHMANN, subjects of the German Emperor, and residing, respectively, at 5 Wilmersdorf-Berlin and Küstrin-Neustadt, Germany, have invented a certain new and useful Combustion Device for Doing Away with Exhaust-Gases in Combustion-Engines, of which the following is a specification.

10 The subject-matter of our invention is means for doing away with the exhaust gases in combustion engines.

The exhaust gases having an offensive smell in combustion engines are due to excess of oil being carried from the cylinder into the exhaust pipe when the exhaust valve is opened and being vaporized by contact with the red-hot surfaces. Also oil is vaporized during the explosions in the cylinder, so that besides oil oil-gases pass into the exhaust pipe.

Now a primary object of our invention is to do away with the offensively smelling clouds of smoke partially by subsequently 25 burning the oil and its vapors in a device, partially by regulating the flow of oil to the cylinder, and rapidly removing any oil which is not completely consumed in the device.

30 In order to obtain combustion it is primarily necessary to supply fresh oxygen to the exhaust gases and oil after they emit from the cylinder, whether by admitting air into the exhaust pipe or combustion device, 35 or by introducing oxidizing substances. The admission of air alone does not suffice, however, since the exhaust gases become cooled so much that automatic ignition is impossible. A flame must be present or be made 40 when it is not existent. The employment of electric ignition is useless because the spark is too small to ignite the vapors of heavy oils. On the other hand, a relatively large flame is necessary which preferably has a 45 certain kinetic energy. Now according to our invention the flame which is due to the explosion and darts out of the cylinder through nozzles a certain distance into the exhaust pipe when the exhaust valve is 50 opened is preferably used for the ignition. For increasing the action, the air may be supplied from within into the flame by suitably constructing the nozzles. Further, under certain circumstances it is necessary to

heat the air preliminarily in a jacketing tube 55 surrounding the device or the exhaust pipe. Also the air can be supplied as compressed air by means of a compressor coupled with the engine.

In order that our invention may be clearly 60 understood we will now describe the same with reference to the accompanying drawing in which one embodiment is represented by way of example.

In said drawing:—Figure 1 is a horizontal 65 section through a number of working cylinders and the exhaust pipe provided with our combustion device, whereas Fig. 2 is a vertical section taken on the bent line A—B in Fig. 1.

70 Referring to the drawing, 1 designates a number of cylinders each having a piston 2, exhaust valve 3 and exhaust pipe 4. To these exhaust pipes we connect a combustion device for the exhaust gases which is preferably common to all the cylinders and in the 75 illustrative embodiment in the drawing comprises a pipe 5 having an approximately rectangular cross-section. This pipe 5 is connected by flanged sockets 6 with the exhaust pipes 4 of the cylinders. The pipe 5 is divided into an air-suction or front chamber 7 and the real combustion chamber 8 which are separated by a partition 9. At the 80 one end, *i. e.* the left end viewing Fig. 1, the pipe 5 is covered by two sieves 10, 11; the chamber inclosed by these is filled with small sieves or steel shavings 12 or similar material for deadening sound and preventing possible danger of fire on the Davy principle. At its other end combustion chamber 8 runs out conically into the real exhaust 85 pipe 13 which is suitably bent and leads to the silencer. Now whenever an exhaust valve 3 is opened the flame which is to be 90 oxidized leaps through a socket 6, front chamber 7 and a nozzle 14 in partition 9 into combustion chamber 8 and there impacts on a tubular member 15 arranged at a definite angle, say 45°, and preferably sawed open 95 lengthwise, through which it is deflected at the proper angle to the exhaust pipe 13. In consequence of the great kinetic energy of the exhaust gases and the rapid succession of explosions in the cylinders an almost constant current is produced from left to right 100 in combustion chamber 8 and sucks air through the sieves 10, 11 energetically in 105

such manner that this air enters both into chamber 7 and chamber 8. Preferably partition 9 is perforated at 16 at the end toward the exhaust pipe so that a suction action is here exercised by the discharging products of combustion on the front chamber 7 and consequently fresh air can constantly enter on the other side through sieves 10, 11 into the front chamber. As 10 the nozzles 14 have a larger cross-sectional area than the tubular sockets 6, the flames darting through chamber 7 and the nozzles carry air from the front chamber and mix with this air and with the air in the combustion chamber very perfectly, so that all 15 the constituents of the exhaust which are unconsumed in the flame are oxidized and the interior of the combustion chamber is completely filled by one large flame. The 20 tubular sockets 6 are preferably made somewhat smaller in cross-sectional area than the exhaust ports 4 of the cylinders, as the flames are then throttled and lengthened thereby. There are, however, cases in which 25 the above described device alone does not suffice, *e. g.* when owing to carelessness of the attendant an excessive quantity of oil passes suddenly into the cylinder and thence into the combustion device. In order to prevent 30 this we preferably specially regulate the supply of oil and provide for the rapid removal of oil arriving in our combustion device. To this end, between each cylinder 1 and the main oil pipe 17, to which oil is 35 supplied generally by a dropping oil-feeder or an oil pump, a supplementary dropping oil-vessel 18 is interpolated which, in all cases when a somewhat large quantity of oil would pass at once into the cylinder owing 40 to improper attendance of the oiling apparatus, stores up the oil and allows it to pass even if rapidly, nevertheless only by drops into the cylinder. To this end the dropping vessel has an outlet 19 narrow compared 45 with the dimensions of the cylinder and regulable in width by a cone 20 adjustable by means of a rod having a screw thread, as clearly shown in Fig. 2.

For removing oil from exhaust pipe 5 and 50 chamber 8, the same have a slanting bottom 5', from which one or more drain pipes 21 having thin walls lead to an optional tank 22 or the like arranged not too near the engine. If necessary, the pipes 21 may have 55 cooling ribs quite close to or only near the combustion chamber 5. The exhaust gases force the oil in the combustion chamber 5 through the pipes 21 into tank 22 where it cannot be vaporized, as when the drain pipes 60 are sufficiently long it is impossible for sufficient heat to be conducted to this tank.

By using our above described means alone or together the exhaust gases can be completely done away with according to the 65 circumstances of each case.

It is to be specially noted that when combustion chamber 5 is made in the manner illustrated in the drawing the sound is simultaneously deadened. Owing to air having to be supplied to the exhaust gases for their 70 complete combustion, a way into the open air is provided for the sound waves. This way is closed for the sound waves, however, by the filling 12 between the perforated walls 10, 11, but on the other hand no great 75 resistance is offered to the admission of air for combustion. As mentioned above, as the combustion chamber opens toward the exhaust side into the usual silencer and this is likewise a resistance, the resistance at 80 the air admission end, say the filling 12 between the perforated walls 10, 11, must be made more effective in its action than the resistance of the ordinary silencer, as otherwise the burned gases would be dammed up 85 in the ordinary silencer, which would cause rebounds, and consequently no air would be sucked into the combustion chamber 5. Besides the sieves illustrated in the drawing, 90 perforated sheet metal, or pervious, non-combustible filling, such as steel shavings, asbestos wool and the like may be used as suitable resistance, which can be influenced optionally in its function as resistance for the sound waves by compressing it more or less. Also rings or partitions displaced relatively to one another, or pipes placed one in another, or an air-vessel or even an ordinary small silencer which is connected by a pipe with the air admission end of the combustion chamber 5 can be employed. The air admission ports may be closed by automatically acting clack-valves. Lastly, the necessary combustion air may be supplied as compressed air, in which event the piston 105 of the compressor forms the resistance for the sound waves.

It will be understood that owing to the provision of the walls 15 on which the flames from the cylinders can impact, the kinetic energy of the exhaust gases is destroyed and the temperature of the flames or exhaust gases is consequently increased.

We claim:—

1. In a combustion device for exhaust gases of combustion engines, the combination with the cylinder exhaust pipe and the engine exhaust pipe, of a combustion chamber disposed between said exhaust pipes, said combustion chamber having an air inlet and a connection with said engine exhaust pipe and between said connection and air inlet a connection with said cylinder exhaust pipe; and a deflector disposed opposite the mouth of said cylinder exhaust pipe and adapted to direct the flame jets entering said combustion chamber from said cylinder exhaust pipe away from said air inlet to induce a suction therethrough.
2. In a combustion device for exhaust

gases of combustion engines, the combination of a plurality of combustion cylinders, a combustion chamber having lateral openings opposite the mouths of the exhaust pipes of said cylinders and provided with an air inlet, an engine exhaust pipe connected with said combustion chamber, and deflectors in said combustion chamber between said air inlet and engine exhaust pipe and opposite the mouths of said cylinder exhaust pipes, said deflectors being adapted to direct the flame jets entering said chamber away from said air inlet for inducing a suction therethrough.

15 3. In a combustion device for doing away with exhaust gases in combustion engines, the combination, with the engine cylinder exhaust pipe and the exhaust pipe of the engine, of a chamber in open relation with the atmosphere and with said exhaust pipes, a partition dividing said chamber into an air-suction chamber and a combustion chamber, said partition having an aperture opposite said cylinder exhaust pipe, and deflecting means on said partition in said combustion chamber opposite said aperture.

20 4. In a combustion device for doing away with exhaust gases in combustion engines, the combination, with the engine cylinder exhaust pipe and the exhaust pipe of the engine, of a chamber in open relation with the atmosphere and with said exhaust pipes, a partition dividing said chamber into an air-suction chamber and a combustion chamber, said partition having an aperture opposite said cylinder exhaust pipe, a nozzle in said aperture, and deflecting means on said partition in said combustion chamber opposite said aperture.

25 5. In a combustion device for doing away with exhaust gases in combustion engines, the combination, with the engine cylinder exhaust pipe and the exhaust pipe of the engine, of a chamber in open relation with the atmosphere and with said exhaust pipes, said chamber being formed at one part by two sieves inclosing a space containing a non-combustible filling pervious to air, a partition dividing said chamber into an air-suction chamber and a combustion chamber, said partition having an aperture opposite said cylinder exhaust pipe, and deflecting

means on said partition in said combustion chamber opposite said aperture.

6. In a combustion device for doing away with exhaust gases in combustion engines, the combination, with the engine cylinder exhaust pipe and the exhaust pipe of the engine, of a chamber in open relation with the atmosphere and with said exhaust pipes, a partition dividing said chamber into an air-suction chamber and a combustion chamber, said partition having an aperture opposite said cylinder exhaust pipe, and deflecting means on said partition in said combustion chamber opposite said aperture, a tank removed from the engine, and a drain pipe in open relation with said combustion chamber and said tank.

7. In a combustion device for exhaust gases of combustion engines, the combination with the cylinder exhaust pipe and the engine exhaust pipe of a combustion chamber disposed between said exhaust pipes and having connections therewith, said combustion chamber being open at one end and provided with previous partitions inclosing a non-combustible previous filling, and a deflector disposed opposite the mouth of said cylinder exhaust pipe and adapted to direct the flame jets entering said chamber from said cylinder exhaust pipe away from said open end to induce a suction through said filling.

8. A combination of a combustion cylinder, a combustion chamber having a connection with the exhaust pipe of said cylinder and provided with an air inlet, and a deflector disposed between said air inlet and the discharge outlet of said chamber and opposite the mouth of said cylinder exhaust pipe, said deflector being inclined to direct the flame jets entering said chamber from said cylinder away from said air inlet to induce a suction therethrough.

In testimony, that we claim the foregoing as our invention, we have signed our names in presence of two subscribing witnesses.
